UNITED STATES PATENT OFFICE.

CAMPBELL SCOTT AND ERNEST L. GALE, SR., OF YONKERS, NEW YORK, ASSIGNEES TO OTIS ELEVATOR COMPANY, OF JERSEY CITY, NEW JERSEY, A CORPORATION OF NEW JERSEY.

AUTOMATIC ATTACHMENT FOR WITHDRAWING PUNCHINGS FROM PUNCHING-MACHINES.

948,382.

Specification of Letters Patent. Patented Feb. 8, 1910.

Application filed March 30, 1906. Serial No. 308,982.

To all whom it may concern:

Be it known that we, CAMPBELL SCOTT and ERNEST L. GALE, Sr., residing at Yonkers, in the county of Westchester and State of New York, have invented a new and useful Improvement in Automatic Attachments for Withdrawing Punchings from Punching-Machines, of which the following is a specification.

10 Our invention relates to pick-offs for punching machines and one of its objects is the provision of simple and efficient means for withdrawing punchings from punching machines with safety.

15 A further object of our invention is the provision of automatic electro-mechanical apparatus for removing the punchings from a punching machine.

Another object of the present invention is 20 the provision of positive means for removing the pick-off from under the punch to prevent said pick-off from being injured.

A further object is to provide in combination with an automatic pick-off device, a 25 plurality of cutters to entirely sever the scrap from the material inserted when a punching is made.

Other objects of our invention will appear hereinafter, the novel combination of 30 elements being pointed out in the claims.

In the accompanying drawings Figure 1 represents in elevation, a punching machine with our invention applied thereto; Fig. 2 represents a plan view of the die of the 35 punching machine, and also our improved attachment; Fig. 3 is a view similar to Fig. 2 but showing the pick-off in another position; Figs. 4 and 5 are views of an automatic electric switch that may be used if desired; Fig. 6 serves to illustrate one form 40 of buffer device that may be used as herein-after explained; Fig. 7 represents a wiring diagram of the circuits and connections; Fig. 8 is an elevational view of a modification in that the operating device for the 45 pick-off is entirely mechanical; Fig. 9 represents a plan view similar to Figs. 2 and 3 but showing the mechanical construction of Fig. 8; and Figs. 10 and 11 are detailed views of the cutters that may be used 50 for separating the scrap entirely from the material inserted each time a punching is made.

Referring to Fig. 1, S designates the standard or support at the upper end of which is mounted the shaft 1 to which is secured the pulley P. B designates a belt connecting some source of power with the pulley P, which latter transmits the power to the shaft 1, and to the mechanism operated thereby, for actuating the punch carrier 3. Any suitable type of punching machine may be used, and such a machine is not shown complete in the drawings for the reason that various kinds are well known to those skilled in the art.

6 designates a bed plate for the die carrier 4, the die D' being shown in Fig. 2. Obviously this die may be of any shape desired and the punch made to correspond thereto. In this instance a circular die is shown with a central opening 5 so that the punching machine will produce laminations for an armature of a dynamo-electric machine. Any suitable means may be used for securing the dies in place and making them removable or adjustable.

Pivoted at 2 to the frame of the punching machine is the lever L, the upper arm of which is adapted to be struck by the cam C 80 secured to the shaft 1. The lower end of the lever L carries an arm 29 which is provided with a slot 30 at its outer end, and through this slot projects a pin 86 which is secured to the outer end of the lever 28. Connected to the same pin is a link 32 slotted at 31 so as to have some lost motion at certain times. The link 32 is pivoted at 33 to the arm 10 carrying the pick-off device 87 at its outer end. The pick-off device in this instance 90 comprises an electro-magnet 15 provided with comparatively long poles 16, 16, which are adapted to pick up the punching and scrap D and 48, respectively, when the magnet is energized.

When the punching machine is operated and the shaft 1 makes a complete revolution, the cam C strikes the lever L and moves the arm 29 to the left. For a certain period of time there is a free motion of said arm 29 by reason of the slot 30 in the outer end thereof. When, however, the outer end of the slot is reached, pin 86 is struck and arm 28 of the electric switch 27 moved to the left. This has the effect of energizing the 105 electro-magnet E, which thereupon draws in

wardly its core 7 and moves to the right the link 8 which is pivoted at 9 to the pick-off arm 10. The arm 10 will thereupon be moved to the position indicated in Fig. 3, but while doing so the link 21, which is pivoted at 22, will be actuated until the end of its slot 23 is reached, when the switch 25 will be operated. The operation of the latter switch will effect the energization of the 10 pick-off magnet 87. At substantially the same time or a short time thereafter, the inner end of the slot 31 of the link 32 which is pivoted at 33 to the arm 10, is reached, the switch arm 28 will be thrown to its 15 original position to effect the deenergization of the electro-magnet E. The spring 12 which is fastened to the magnet frame at 13 and to the arm 10 at 14, will now act to move the pick-off arm 10 to its original position.

20 A bracket 20 secured to the bed plate 6 carries a buffer device 11 which comprises a spring-pressed stem 19 against which the arm 10 strikes. When the electro-magnet 25 87 is moved inwardly the stem 18 of the buffer device 17 carried by the pick-off may strike against some part of the punch to bring the arm 10 to a gradual stop. Also secured to the bed plate is a bracket 68 on 30 which is mounted an inverted V-shaped slide 46, both sides of which may be of the same length, or that side for the punchings may be longer than the other as indicated at 47 in Figs. 1, 2, and 3. After the pick-off device has been operated and returned to normal position with the punching and scrap as indicated in Fig. 2, and magnet 87 is deenergized, the punching D and the scrap 48 will be dropped over the inverted 35 V, the punching going to one side of the slide 46, and the scrap to the other side, thus immediately separating the scrap from the punchings.

40 The electric switch as shown in Figs. 4 and 5, may be varied as desired and the particular form here illustrated is merely set forth to show some means for accomplishing the objects of our invention. In this instance, a casing 40 has pivoted within it, two levers, 28 and 37, at 34 and 35, respectively. The arm 28 extends out from one end of the casing, and has a pin-and-slot connection with the links 29 and 32. Its inner end carries an anti-friction roller 35, which is preferably composed of insulation. When the arm 28 is moved to the right the roller 35 is moved to the left over the arm 36 and the bell crank lever 37 against the action of the spring 39. When this occurs, the arm 28 is moved out of engagement with the contact 41 which is mounted on the insulation 42. In order to hold the arm 28 in the position to which it has been moved, a pivoted lever 44 may be used and made to bear against the laterally extending pin 43

on the arm 28 by means of the spring 45. To prevent the arm 28 from being thrown too far, stops 27 in the casing 40 may be used.

50 In the event that while the pick-off device 70 is in the position indicated in Fig. 3 and directly under the punch, the spring 12 should become inoperative, the punch would injure the pick-off device, and injury would also be done to the punching machine itself. In 55 order to lessen the liability of such an accident, we have provided positive means for ejecting the pick-off electro-magnet from under the punch each time it is moved downward. This positive means comprises a 60 swinging arm 51 pivoted at 50 to a bracket 49 secured to the punching machine frame. The outward movement of this arm is limited by the pin 89 on the bracket 49 (Fig. 1) and it is held against such pin by means of 65 the spring 71. When the arm 10 is moved inwardly to its position indicated in Fig. 3, it strikes the lower end 55 of the lever 51 and moves the cam portion 52 thereof against the roller 53, which is mounted on a bracket 90 54 secured to the punching machine frame. The punching machine and withdrawing attachment are so adjusted that the pick-off electro-magnet will reach its innermost position at about the same time that the punch 95 assumes its normal position. Now, if the punch should be again operated and the arm 10 should remain in its inner position for any reason whatever, the anti-friction roller 53 would strike against the cam 52 and 100 positively move the arm 51 outwardly and consequently also its lower end 55 with the arm 10, thus ejecting the electro-magnet 87 from under the punch and preventing any 105 injury to said magnet or to the punching machine.

110 In Fig. 9 at 56, 56, are shown small cutters for entirely severing the scrap from the material inserted, so that a piece of scrap 48 and the punching D will both be withdrawn together to the position shown in Fig. 2. The cutters 56 may be of any type desired and varied at will, so long as it efficiently cuts the scrap from the material at the same time the punching is made. In this instance we have shown a cutting blade 58 on a carrier 57 which is fastened at 65 to a cap 59. This cutter has a downwardly extending rod 66, around which is placed a spring 67 for returning the cutter to its normal position as indicated in Fig. 10. When the punch comes down it strikes against the top of the cutter-carrier 57, and moves the same downwardly so as to effect the cutting of the scrap from the material inserted at the point 90. To permit part of the material cut to be bent, a recess 59' is formed in the plate 60, and a suitable guide 91 secured to the cap 59 insures the proper cutting. The guide 91 moves in the guide-way 62 and is limited in 120 125 130

its upward movement by the plate 61 which is secured in any suitable manner to the block 63. If desired, a buffer device 70 composed of rubber or other similar resilient material may be used to prevent wear or injury to parts of the cutter when the same is operated.

In the modification illustrated in Fig. 8, an anti-friction roller C' is mounted near the periphery of the annulus 92 which is keyed to the shaft 1'. This roller C' is arranged to strike against the lever L' which is pivoted at 2' to the frame of the punching machine. A spring 73 acts on the arm 74 of the lever L' to move the latter against the stop 72. To the extreme lower end of the arm 74 is pivoted at 75, a latch arm 83 which is provided with a hook 84 at its outer end, and a cam 77 at an intermediate portion. This cam is adapted to ride up on the roller 76 which is mounted on the frame of the punching machine. The vertical portion 79 of the hook 84 is arranged to engage the upward projection 80 of the pick-off arm 10' and move the latter to its inner position when the shaft 1' makes a complete revolution. In this event, after the arm 10' has been actuated and given sufficient momentum to carry it to its innermost position, the cam 77 will ride up on the roller 76 to free the hook 84 from the projection or lug 80. The spring 12 may then act as before to return the arm 10' to its original position. Force is exerted on the arm 10' only during about one quarter of the revolution of the shaft 1' when the roller C' starts from a position corresponding to that shown in Fig. 8. It is obvious, however, that the roller C' will be moved only a pre-determined distance when the hook 84 will be released by reason of the cam 77 riding up on the roller 76; and when the roller C' again moves away from the lever L' the spring 73 acts on the arm 74 to return the latch-arm 83 to its original position. In the event that the arm 10' reaches its original position before the latch-arm 83 reaches its normal position, the face 78 of the hook 84 will slide over the projection 80 and the latch-arm 83 will fall into the position indicated in Fig. 8.

The operation of our invention may be explained as follows. Assuming that the punching machine has been operated in the usual manner and the cam C therefore revolved, the arm or link 29 will be moved to the left a pre-determined distance until the end of the slot 30 strikes against the pin 86 to move the arm 28 into the position indicated in Fig. 5. This will effect the engagement of the contacts 41 and 88, and by reference to Fig. 7 the circuit may easily be traced from the + main to the arm 37, contacts 88 and 41, wire 95, electro-magnet E, wire 96, to the - main. The electro-magnet E will thereupon be energized and its core

7 and connecting parts thrown inwardly to move the pick-off device 87 to the position indicated in Fig. 3. A short time after or upon reaching this position, the inner end of the slot 31 of the link 32 strikes against the pin 86 to return the arm 28 to its normal position, and therefore effect the disengagement of the contacts 41 and 88 and the consequent de-energization of the electro-magnet E. Substantially at the same time the inner end of the slot 23 of the arm 21 strikes against the pin carried by the switch-arm 24 and operates the latter to close the switch 25 and thus connect the contacts 96 and 97 as indicated in Fig. 7. A circuit will now be closed from the + main through arm 24, contacts 96, 97, wire 98, electro-magnet 15, and wire 99 to the - main. The pick-off electro-magnet will therefore be energized to attract and hold the punching and scrap which are of magnetic material. The electro-magnet E having been de-energized as stated, the spring 12 will act to return the arm 10 to its original position, and in doing so, the arms 21 and 32 will have free movement by reason of the slots 23 and 31 respectively, in the outer ends thereof. The arm 28 will be left in its position last placed so that the contacts 41 and 88 remain disengaged. But upon the arm 10 reaching its normal position, the inner end of the slot 23 in the link 21 strikes against the pin carried by the arm 24 to operate the switch 25 and open the contacts 96, 97. At this time the punching D and scrap 48 are above the V 46, and when the pick-off electro-magnet is thus de-energized, the punching will fall to one side and slide down the way 47 and the scrap 48 will fall to the other side.

It should be noted that although the buffer device 17 when its stem 18 strikes against a part of the punch and prevents substantial shocks and jars to the pick-off electro-magnet and arm, the spring-pressed lever 51 will tend to have the same effect and will also assist in overcoming the inertia of the moving parts and start the same in their return movement. If desired, furthermore, the cam 52 may also be so designed with respect to the punching machine and the withdrawing attachment, that each time the punch is operated the arm 10 will be given a positive thrust to assist in returning it to its normal position. By changing the leverages and the connections, any degree of rapidity of operation for withdrawing the punchings may be obtained. In other words, the punching machine may be operated as rapidly as desired, and the withdrawing attachment adjusted to correspond in rapidity therewith.

The operation of the mechanical device shown in Fig. 8 is substantially similar to the operation of the construction shown in Fig. 3.

- Fig. 1. In both cases the cutters 56, 56, illustrated in detail in Figs. 10 and 11, should be used, or some other cutter which will have the same effect. The positive 5 ejecting device should be used in any case for the sake of safety so that in no event can the punch injure any of the parts by reason of the pick-off electro-magnet getting caught between the punch and the die.
- 19 It will now be apparent that we have constructed a simple and efficient device for withdrawing punchings from punching machines such as is absolutely safe, in that it does not require the insertion of the workman's hands under the punch to take out 25 the punchings and scrap. This has often been the source of serious injuries for the reason that the punch might come down while it was being endeavored to remove 30 the punchings and scrap. It should also be noted that a positive ejecting device has been provided to prevent the punching machine or the attachment thereto from being injured. But we do not desire to be limited 35 to the exact construction of detail and arrangement of parts herein disclosed, as various modifications may be made by those skilled in the art without departing from the spirit and scope of our invention.
- 30 What we desire to claim and have protected by Letters Patent in the United States is:—
1. In a pick-off for punching machines, the combination with a punching machine, and means for automatically withdrawing by attraction the material from the said machine after it is punched.
  2. In a pick-off for punching machines, the combination with punching apparatus, and electro-mechanical means for automatically withdrawing the punchings from such apparatus.
  3. In combination with a punching machine, of a pick-off device for automatically withdrawing punchings from the die, and means co-acting with the punching machine for operating said pick-off device.
  4. In combination with a punching machine, of a pick-off device for automatically withdrawing punchings from the punching machine, electric means for actuating said pick-off device, switch mechanism for controlling said electric means, and connections actuated by the punching machine for operating said switch mechanism.
  5. In combination with a punching machine, of a swinging arm, an electro-magnet carried by said arm for picking punchings off from the die of the punching machine, and means for automatically actuating said arm.
  6. In combination with a punching machine, of a swinging arm, an electro-magnet carried thereby, means co-acting with the punching machine to automatically move

said arm to bring said electro-magnet in proximity to the punchings, and means for energizing and de-energizing said electro-magnets at pre-determined times.

7. In punching machines, the combination with a pick-off device comprising a swinging arm, and means operated upon movement of the punch for positively actuating said arm out of the path of the punch.

8. In punching machines, an attachment for automatically withdrawing by attraction punchings from the die, and positive means for preventing any part of said attachment from being engaged by the punch.

9. In punching machines, the combination with an arm, of an electro-magnet carried thereby, means for moving said arm to bring the electro-magnet into proximity to the punchings, and a device operated upon the movement of the punch to punching position to positively actuate said arm to take the electro-magnet out of the path of the punch.

10. In punching machines, the combination with a punching machine, of a swinging arm, an electro-magnet carried by said arm, an actuating device for moving said arm to bring the electro-magnet into proximity to the punchings on the die, means for energizing said electro-magnet, means for returning the arm and electro-magnet to normal position, and a safety device for preventing the electro-magnet from being struck by the punch.

11. In combination with a punching machine, of a swinging arm, an electro-magnet carried thereby, means co-acting with the punching machine for automatically swinging said arm upon the operation of the punch, an automatic switch for energizing said electro-magnet when in proximity to the punchings, means for returning said swinging arm to its normal position, and connections between said swinging arm and switch for automatically de-energizing said electro-magnet when the same assumes its normal position.

12. The combination with a punching machine, of a swinging arm, an electro-magnet carried by said arm, an additional electro-magnet connected to said arm to actuate the same and swing said first-named electro-magnet into proximity to the punchings, an electric switch, means co-acting with the punching machine for operating said electric switch to effect the energization of the second-named electro-magnet, an additional switch, a connection between said arm and said additional switch to operate the latter and effect the energization of the first-named electro-magnet, and means for returning said swinging arm to its normal position, and automatically de-energizing said first-named electro-magnet.

13. In punching machines, the combina-

- tion with a swinging arm, of an electro-magnet carried at the outer end thereof, an electro-magnetic device connected to said arm at an intermediate point, automatic electrical means co-acting with said punching machine to effect the operation of said electro-magnetic device upon the actuation of the punch, an electrical switch, and a connection between said electrical switch and the swinging arm for effecting the energization of the electro-magnet at the outer end of the arm when said electro-magnet is in proximity to the punchings, and for effecting the deenergization of said electro-magnet when said arm assumes its normal position. 10
14. In a punching machine, the combination with the dies, of a device for withdrawing by attraction punchings from the path of the dies, means for operating the said device, and means for effecting a separation of the punching and the scrap. 20
15. In a punching machine, the combination with an electro-magnetic pick-off device for withdrawing the punchings from the punching machine, of electro-magnetic means co-acting with the punching machine for automatically operating said pick-off device, and means adjacent to said pick-off device when in normal position for effecting the separation of the punching and the scrap. 30
16. In a punching machine, the combination with a pick-off device for automatically withdrawing punchings from punching machines, of apparatus co-acting with the punching machine for operating said pick-off device, and a device for automatically separating the punching from the scrap, by operating upon the punching and scrap to allow them to fall apart from each other. 35
17. In a punching machine, the combination with a punch and a die, of means for separating the scrap and the punching entirely from the material inserted, and means for withdrawing by attraction both the scrap and the punching from the machine. 40
18. In a punching machine, the combination with a punch and a die, of a plurality of cutters for separating the scrap as well as the punching entirely from the material inserted, and automatic electro-mechanical means for withdrawing both the scrap and punching from the machine. 50
19. In a punching machine, the combination of a punch and a die, and diametrically arranged cutters or knives for severing the scrap from the material when the punching is made. 55
20. In a punching machine, the combination with a punch and a die, of diametrically arranged cutters or knives for severing the scrap from the material inserted when a punching is made, an automatic electro-mechanical device for withdrawing the punching and scrap from the punching machine, and means for automatically separating the punching from the scrap. 65
21. The combination in a punching machine with a punch and a circular die having a central opening, of cutters or knives arranged opposite each other for entirely severing the scrap from the material inserted when a punching is made, an electro-magnetic pick-off device for withdrawing the punchings and scrap from the punching machine, and means co-acting with the punching machine for automatically operating said pick-off device. 70
22. The combination with a punching machine of means for withdrawing punchings therefrom, and buffer mechanism for the movable member of said means. 75
23. In a punching machine, the combination with means for withdrawing punchings from punching machines comprising a movable member, of a buffer device carried by said member and arranged to strike against a part of the punching machine, and an additional buffer device arranged to be struck by said member upon returning to its normal position. 85
24. In a punching machine, the combination with a swinging arm, of an electro-magnet carried thereby, a buffer device also carried by said arm, and arranged to strike against the punch, an additional buffer device arranged to be struck by the arm upon returning to its normal position, electro-magnetic means co-acting with the punching machine for automatically swinging said arm and electro-magnet toward the punch and means for returning said electro-magnet to normal position. 90
- In testimony whereof, we have signed our names to this specification in the presence of two subscribing witnesses.
